DESIGN FOR A SPECTACLE FRONT

George E. Nerney, Attleboro, Mass., assignor to
Bay State Optical Company, Attleboro, Mass.,
a corporation of Maine

Application November 20, 1937, Serial No. 73,068

Term of patent 7 years

To all whom it may concern:

Be it known that I, George E. Nerney, a citizen of the United States and a resident of Attleboro, in the county of Bristol, State of Massachusetts, have invented a new, original, and ornamental Design for a Spectacle Front, of which the following is a specification, reference being had to the accompanying drawing, forming a part hereof.

In the drawing,

Figure 1 is a front elevation of a spectacle front showing my new design;

Figure 2 is a top plan view of the spectacle front shown in Figure 1; and

Figure 3 is an enlarged fragmentary perspective view of a portion of the spectacle front shown in Figure 1 and looking in the direction of the indicating arrows.

I claim:

The ornamental design for a spectacle front substantially as shown.

GEORGE E. NERNEY.
